CARRIER WAVE TRANSMISSION SYSTEM

Filed May 3, 1921

Patented Nov. 6, 1923.

1,473,433

UNITED STATES PATENT OFFICE.

ARTHUR W. KISHPAUGH, OF EAST ORANGE, NEW JERSEY, ASSIGNOR TO WESTERN ELECTRIC COMPANY, INCORPORATED, OF NEW YORK, N. Y., A CORPORATION OF NEW YORK.

CARRIER-WAVE TRANSMISSION SYSTEM.

Application filed May 3, 1921. Serial No. 466,477.

To all whom it may concern:

Be it known that I, ARTHUR W. KISHPAUGH, a citizen of the United States of America, residing at East Orange, in the 5 county of Essex and State of New Jersey, have invented certain new and useful Improvements in Carrier-Wave Transmission Systems, of which the following is a full, clear, concise, and exact description.

10. This invention relates to carrier wave transmission systems.

According to present practice in this art, high frequency oscillations are produced, controlled or modified in accordance with 15 signals or impulses to be sent, and transmitted to a distant station. It is often desirable to be able to control the source of oscillations from a remote point such as an operator's switchboard. Particularly is 20 this true in duplex radio transmission if the local radio transmitting and receiving apparatus are separated by a considerable distance and the operator's position is at the receiving apparatus or any other point remote 25 from the transmitter. A feature of this invention is a remote control of the source of high frequency oscillations.

In radio systems of the type described, it is highly desirable for the operator at the 30 remote position to know if the radio transmitting system is functioning properly and accordingly whether the transmitting antenna is being supplied with radio frequency current of the proper frequency. 35 An additional feature of the invention consists in an indicator for showing the presence in the transmitting antenna of radio frequency current of the proper frequency and for giving an alarm at the transmitter 40 station when this current fails or materially changes frequency.

The ordinary three-element electric discharge device having a cathode, an anode, and an impedance control element requires a 45 source of heating current for the cathode and a source of space current. If the full working voltage of the space current source be applied to the electrodes of the device before the cathode is heated and if the magnitude 50 of the space current be large it may result in damage to or destruction of the discharge device. A feature of the present invention is the provision of means for safeguarding such a device against high space current

voltages and excessive space current until 55 its cathode is fully energized.

According to one embodiment of this invention a radio system is provided with local radio receiving apparatus and radio transmitting apparatus separated therefrom by 60 a considerable distance. An operator at the receiving apparatus is provided with facilities for connecting the system to signal lines to permit carrier wave transmission of signals originating in these lines. The 65 transmitting apparatus consists of an electric discharge oscillator of well-known type having direct current generators for supplying cathode heating current and space current. The apparatus at the operator's 70 position includes a switch to open and close the circuit of a remote relay which controls the field of the cathode heating current generator. This generator in turn supplies field current to the space current generator. 75 A time-limit relay energized from the cathode heating circuit or the space current circuit serves to delay application of the full voltage of the space current generator and to reduce the space current of the electric 80 discharge device until its cathode has had time to become fully heated. When the electric discharge oscillator is fully in operation, it supplies radio frequency oscillations to a radio transmitting antenna. A 85 circuit is coupled to this antenna to abstract a small portion of the energy supplied thereto in order to control an indicator at the remote operator's position, thus enabling the operator to ascertain whether or not 90 the transmitting antenna is in operative signal transmitting condition.

The novel features which are considered 95 characteristic of the invention are set forth with particularity in the appended claims. The invention itself, however, both as to its organization and method of operation together with further objects and advantages thereof will best be understood by reference to the following description taken 100 in connection with the accompanying drawing in which Figure 1 shows diagrammatically a circuit arrangement which may be employed in carrying the invention into effect and Figure 2 shows a modification 105 of a detail of Figure 1.

Referring to Figure 1, a plurality of signal lines 1 terminating at the ordinary tele-

phone exchange are associated with the signal circuit 2 of a carrier wave transmission system. The receiving apparatus of the carrier wave transmission system indicated generally by R is shown at the left of the broken line C C. The transmitting apparatus designated generally by T is shown at the right of this line. The receiving apparatus comprises a receiving antenna 3 5 preferably tuned to the wave length of the carrier waves which it is desired to receive, the demodulating apparatus 4 for demodulating the received waves to produce the desired signal, and a filter 5 for transmitting 10 the demodulated signal currents with negligible attenuation while substantially suppressing currents of other frequencies. The signal circuit 2 is terminated at the operator's position in a balancing network N for 15 simulating its impedance and that of the average circuit 1 or other circuit connected thereto at the frequencies of all currents to be transmitted over circuit 2. The incoming 20 channel 6 from the radio receiving apparatus 25 and the outgoing channel 7 leading to the radio transmitting apparatus are conjugately connected to the signal circuit 2 by means of the hybrid coil or balanced transformer 8 in well-known manner. The outgoing channel 7 includes a filter 9 similar in every respect to filter 5.

The transmitting apparatus comprises an oscillator O, a variable impedance device M, and the thermionic amplifier A. The oscillator includes two electric discharge devices 10 connected in parallel and each having the usual cathode, anode and impedance control element. The alternating current output circuit of the devices 10 may be 30 traced from their anodes by way of condenser 11 and primary winding 12 in parallel, and condenser 14, to the cathodes. Primary winding 12 is inductively coupled to secondary winding 13 included serially 35 in the circuit of transmitting antenna 15. The primary winding 16 also included serially in the antenna circuit is inductively coupled to secondary winding 17 and serves to feed back oscillations from the 40 antenna circuit to the alternating current input circuit of devices 10 which includes winding 17 and capacity element 18 in series. An inductometer winding 19 enables variation 45 of the tuning of the antenna 15 which serves as the frequency determining circuit for the oscillator. The variable condenser 11 serves to so change the constants of the interior circuit as to prevent oscillations 50 therein. The interior circuit comprises winding 17, condenser 18, condenser 14, elements 11 and 12 in parallel and the inherent capacity between the anodes and control elements. Condenser 11 therefore serves to 55 prevent the absorption of power by interior oscillations. It further serves to improve

the power factor of the plate current, in a measure compensating for the leakage reactance of the winding 12. Modulation is accomplished by means of the constant current system of R. A. Heising fully disclosed 70 at page 360, Proceedings of A. I. E. E., Volume 38, No. 3. The variable impedance device M comprises two electric discharge devices 20 connected in parallel. A generator G_B having a separately excited field 75 winding F_B supplies space current to devices 10 and 20 in parallel over a path including constant current choke 21, inductance 22, automatically operating circuit breaker 23, and left-hand blade of switch 80 24 to the positive terminal of generator G_B. From the negative terminal of this generator, the space current path may be traced by way of the right-hand blade of switch 24, series inductance 25, resistance 26, and resistance 27 to the cathodes of devices 10 and 20. Connected in shunt across the space current circuit are capacity elements 39, which in conjunction with series inductances 22 and 25 85 90 serve to prevent commutator ripples and other fluctuations in the voltage of source G_B from affecting the space current and also serve to prevent high frequency oscillations from being impressed upon the generator 95 G_B through the space current circuit. Filament heating current is supplied by a generator G_A having a series field winding F and a shunt field winding F_A. In series with the shunt field winding is a variable 100 resistance 28 and a high resistance 29 which is adapted to be short-circuited upon closure on its contact of an armature 30 of remote control relay 31. The separately excited 105 field winding of generator G_B is connected directly across the output terminals of generator G_A to be supplied with exciting current therefrom. A switch 32 is interposed in the filament heating circuit to enable this 110 circuit to be opened when desired. The input circuit of thermionic amplifier A is coupled by a transformer 33 to the outgoing channel 7. The secondary winding of the transformer is shunted by a resistance 34 to improve the impedance characteristic of 115 the transformer 33 in well-known manner. Amplifier A is supplied with cathode heating current from source G_A and is supplied with space current by source G_B over a path identical with that for devices 10 and 20 except that instead of passing through the constant current choke 21, the space current for the amplifier traverses a resistance 35 to reduce the effective voltage impressed across the electrodes of the amplifier. Resistance 35 is shunted by a capacity element 36 to reduce the impedance of the output circuit of the amplifier for the amplifier signal currents. A transformer 37 couples the 120 output circuit of amplifier A with the in- 125

- put circuit of variable impedance device M. A resistance 38 which may be of the order of 10,000 ohms and therefore of small magnitude with respect to the input impedance 5 of devices 20 is included in shunt to the secondary winding of transformer 37 to stabilize the impedance connected to this winding. A radio frequency choke 40 which freely passes low frequency signal 10 current serves to prevent radio frequency oscillations from being impressed upon and dissipated in the circuits of the variable impedance device and the space current generator. The cathode of each electric discharge 15 device is equipped with an individual regulating resistance 41 for varying the heating current.
- The input circuit of amplifier A may be traced from the impedance control element 20 of the amplifier through the secondary winding of transformer 33 to a point in resistance 26 and thence through the upper portion of this resistance and resistance 27 to the cathode. Since space current passes 25 through resistances 26 and 27 there will be a potential drop between the cathode and the point in resistance 26 and the control element or grid of the amplifier will accordingly be maintained at a potential negative 30 with respect to that of its cathode. The input circuit of discharge devices 20 is connected to the lower terminal of resistance 26 and their impedance control elements are accordingly maintained at a potential still 35 more negative than that of the control elements of the amplifier. The grid leak path of the oscillator includes a resistance element 42 connected to the upper terminal of resistance 26 and the control elements or 40 grids of the oscillator are maintained at a less negative potential determined by the potential drop across resistance 27 in consequence of the space current flowing therethrough. The grids of the amplifier, variable impedance device and oscillator are accordingly each maintained at such negative potentials with respect to their individual cathodes as to reduce their respective space currents to extremely small values. 45
- Oscillations are not produced under these conditions. A time-limit relay 43 is connected across the terminals of generator G_A. This relay when energized closes its normally open contacts 44 to short-circuit resistance 27. As soon as resistance 27 is short-circuited the grids of the various discharge devices become less negative and permit more space current to flow, thus rendering each of the devices operative and causing 50 radio frequency oscillations to be produced in the antenna. This action is further increased by the reduction of the external resistance in the space current circuit when resistance 27 is short-circuited, in effect increasing the effective space current voltage. 55
- In order to prevent surges in the space current circuit in consequence of opening or closing of contacts 44, a path including a resistance 45 and a capacity element 46 in series therewith is shunted across the terminals of resistance 27. 70
- Connected serially in the antenna circuit is the primary winding 48 of a transformer 49 to which is connected a rectifying electric discharge device 50 comprising a thermionic 75 cathode and an anode. A portion of the secondary winding of transformer 49 is connected to the terminals of the cathode to supply heating energy thereto and the remainder of this winding is connected 80 across the cathode and anode to supply rectified energy to a relay 51 in series therewith. Relay 51 is provided with an armature 52 controlling a circuit 53 which is simplex over a talking circuit 54 extending 85 from the radio transmitting apparatus to the operator's position at the radio receiving apparatus or elsewhere. The circuit 53 includes a relay 64 grounded through battery at the operator's position and serving by means of its armature 55 to control the energization of the signal lamp 56. Armature 52 also controls a circuit 65 which includes a current source 66, a bell or other alarm 57 and which is open at the normally 90 open upper contacts of time limit relay 43. This alarm is therefore actuated whenever relay 43 is energized and relay 51 is not energized. Telephone sets 58 of conventional design are shown associated with talking circuit 54 to permit communication from the operator's position to the transmitting station without recourse to outgoing channel 7. 95
- A switch 59 in circuit 60 at the operator's 105 position permits the remote control of relay 31. The generators G_B and G_A are directly connected or driven in any suitable manner by a constantly acting device 61 shown as a three-phase alternating current motor. 110
- Figure 2 illustrates a modification of the arrangement for controlling indicators 56 and 57 at the operator's position and radio transmitter respectively. According to this modification, the secondary winding of 115 transformer 49 is included with a variable capacity 62 in a closed tuned circuit such as is ordinarily used in wave-meter circuits. This circuit also includes a thermo-couple 63 which may be connected to the relay 51 120 to supply an energizing E. M. F. thereto. 125
- The operation of the circuits described may now be explained. As illustrated the alternating current motor 61 is in operation and generators G_A and G_B are operating at full speed. Resistance 29 in the shunt field circuit of generator G_A prevents this generator from building up its voltage and accordingly generator G_B is without exciting current. There are therefore no oscillations 130

in the antenna 15 and relay 51 is deenergized and indicators 56 and 57 indicate this condition at the operator's position at the receiving apparatus and at the ratio transmitter respectively. If the operator receives a call either over the radio receiving apparatus 3, 4, 5 or over one of the signal lines 1, or for any reason whatever desires to put the radio transmitting apparatus in operative condition, it is merely necessary to close switch 59. Relay 31 will then be energized pulling up armature 30 to short-circuit resistance 29 and permit generator G_A to build up its voltage. Generator G_A will therefore supply heating current to the cathodes of each of the electric discharge devices, energizing current to the time-limit relay 43, and field current to generator G_B . Generator G_B thereupon builds up its voltage and supplies space current through resistances 26 and 27 to each of the electric discharge devices. After sufficient time has elapsed to permit the cathodes to become fully heated, time-limit relay 43 operates to close contacts 44, short-circuiting resistance 27. This decreases the normal negative potential on the grids or control elements of the amplifier and discharge devices 10 and 20 and permits full magnitude space current to flow through each of these devices. The oscillator thereupon produces radio frequency oscillations in the antenna 15 and a portion of this radio frequency energy is supplied by a transformer 49 through the rectifier 50 or the thermo-couple 63, as the case may be, to operate relay 51 and thus give an indication at the operator's position that the transmitting apparatus is in operative condition. The operator noting this indication may now make the necessary connections for duplex radio signaling.

The modification of Figure 2 presents the added advantage that the indicators 56 and 57 show not only the presence of radio frequency current in the antenna, but also indicate that this current is of the proper frequency. If for any reason the supply of radio frequency oscillations to the antenna fails the alarm 57 will immediately show this at the transmitter position and if the modification of Figure 2 including the circuit 49, 62, 63 tuned to the desired carrier frequency be used, the alarm will indicate not only failure of radio power in the antenna, but also any marked change in frequency.

The time-limit relay 43 may be any type of slow acting element and it may be connected in various other ways without departing from the spirit of the invention. For example its operating or energizing winding may be connected in shunt to resistance 26 instead of across the filament heating circuit as illustrated or it may be inserted directly in series in the space cur-

rent circuit between the points 70 or 71. In this case the relay need not be slow acting since the time element is given by the time required for the space current itself to build up to sufficient value to energize the relay.

Although the features of the invention have been described and illustrated as embodied in a specific radio system, it is to be understood that they are not to be restricted thereto. Obviously the receiving and transmitting antenna may be replaced by conductive carrier wave circuits. Moreover, certain of the features of the invention are capable of use generally without regard to signal transmission.

What is claimed is:

1. In combination, means for transmitting high frequency waves, generators for supplying energy thereto, a control station remote from said means, said control station having means for controlling said generators to render said transmitting means active.

2. An oscillator comprising an electric discharge device having a thermionic cathode and an anode, a generator for supplying space current to said device, a second generator for supplying heating current to said cathode and exciting current to the field of said first generator, a remote control station, and means at said station for controlling the energization of said second generator.

3. A radio system comprising radio transmitting apparatus, a signaling line for connecting said system with a subscriber's station for communication by said subscriber through said transmitting apparatus, power sources therefor, an operator's station remote from said transmitting apparatus, means at said operator's station for controlling the connection of said power sources to said transmitting apparatus to render the transmitting apparatus active.

4. A radio transmitting station comprising a vacuum tube oscillator having a cathode and an impedance control element, local generators connected respectively to said cathode and to said cathode and anode for supplying cathode heating current and space current, a constantly energized motor directly connected to said generators for supplying mechanical energy thereto, a remote control station and means thereat for controlling the excitation of said generators.

5. An electric discharge device having two electrodes one of which is a thermionic cathode, a high voltage generator for supplying space current to said electrodes, a low voltage generator for supplying heating current to said cathode, a field winding for said low voltage generator, a resistance in series therewith of such magnitude as normally to prevent excitation of said low voltage generator, a field winding for said high

- 6 voltage generator connected across the output terminals of said low voltage generator, a remote control station, and means at said remote control station for short-circuiting 5 said resistance to enable said low voltage generator to be excited.
6. A high frequency transmitting station comprising a source of oscillations and a high frequency transmission conductor, a remote control station having an indicator and means associated with said transmission conductor and controlling said indicator to indicate the presence in said conductor of oscillations of a desired frequency in combination 10 with a main signaling channel connecting said transmitting station and said remote control station.
7. A high frequency station comprising a source of oscillations, a high frequency transmitting conductor associated therewith, a remote control station, a rectifier coupled to said antenna, and an indicator at said remote control station controlled by said rectifier to indicate the presence of oscillations in 20 said antenna in combination with an alarm device at said high frequency station to indicate failure of said rectifier.
8. A radio transmitting station comprising an oscillator and a radiating conductor associated therewith, a tuned circuit coupled to said conductor, a remote control station, a visual indicator thereat, and means controlled by said tuned circuit for operating said indicator to indicate the presence in 30 said conductor of oscillations of a desired frequency.
9. A radio transmitting station comprising a transmitting antenna, means for supplying high frequency oscillations thereto, a remote control station, means other than signaling mechanism at said remote control station, for controlling said supplying means, and means at said remote control station to indicate the presence of high frequency oscillations in said antenna prior to 40 and during the transmission of signals.
10. A radio system comprising radio transmitting apparatus, power sources therefor, an operator's station remote from said transmitting apparatus, means at said operator's station independent of means for transmitting through said apparatus for controlling the connection of said power sources to said transmitting apparatus to 50 render the transmitting apparatus active, an antenna energized by said transmitting apparatus, and means at said operator's station for indicating energization of said antenna.
11. A radio system comprising transmitting apparatus and receiving apparatus, an operator's station, conductive signaling lines terminating at said operator's station, means at said station for connecting any of said lines to said transmitting and receiving ap- 60
- paratus, a source of radio frequency power for said transmitting apparatus, and means at said station for indicating the operative condition of said source of power.
12. A radio system comprising transmitting and receiving apparatus, a central operator's station remote from said transmitting apparatus, a power source at said transmitting apparatus, a telephone line extending from a point adjacent said transmitting apparatus to said station, and means associated with said line for indicating at said station the operative condition of said transmitting apparatus. 70
13. An electric discharge device having a thermionic cathode and an anode, means for supplying heating current to said cathode, a source of space current for said device, and means for delaying the application of the full E. M. F. of said space current source to 80 said device until said cathode has become energized. 85
14. A thermionic discharge device having two electrodes one of which is a thermionic cathode, a source connected to said cathode for supplying heating current thereto, a second source connected to said electrodes to supply space current thereto, a time limit relay having normally open contacts in 90 series in said space current circuit and having an energizing winding connected to said filament heating source whereby the application of the space current source may be delayed for a time after the application of 95 said filament heating source. 100
15. A thermionic discharge device having a filamentary cathode and an anode, a circuit connecting said cathode and anode and including normally open contacts and a source of space current in series, means for supplying heating current to said cathode and a slow acting relay connected in shunt to said cathode and provided with means for closing said contacts when energized. 105
16. A thermionic oscillator having a cathode, an anode and an impedance control element, a source of space current therefor, a resistance connected to the negative pole of said source and in series with the cathode—anode discharge path of said oscillator, a connection from the negative terminal of said resistance to said impedance control element, a switch for short circuiting said resistance and a path in shunt to said resistance and including capacity and resistance in series. 110
17. An electric discharge device having a cathode, an anode and an impedance control element, a source of space current having its positive terminal connected to said anode, and its negative terminal connected through two resistances in series to said cathode, a conductive connection from said impedance control element to the point intermediate to said series resistances where. 120 125 130

by said element is maintained negative with respect to said cathode, a source of heating current connected to said cathode, means for controlling the application of said heating current to said cathode, a time limit relay connected in parallel to said cathode and adapted to be energized simultaneously therewith, and means under the control of

said time limit relay to short-circuit a portion of the series resistance adjacent said 10 cathode to cause said control element to become less negative with respect to said cathode.

In witness whereof, I hereunto subscribe my name this 2nd day of May A. D., 1921.

ARTHUR W. KISHPAUGH.
